CLAIM

The ornamental design for a mobile drive unit, as shown and described.

DESCRIPTION

FIG. 1 is a front, left perspective view of a mobile drive unit; FIG. 2 is a rear, right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the mobile drive unit that form no part of the claimed design.

1 Claim, 8 Drawing Sheets
